PNEUMATIC FOOT SUPPORT

Whitman W. Davis, Burbank, Calif.

Application June 7, 1946, Serial No. 675,154

1 Claim. (Cl. 36—71)

1

This invention relates to cushioned foot supports and, although not thereto restricted, is adapted particularly to the insertable and removable type of insert or pad, constructed of two or more plies of suitable material, such as rubber, canvas-reinforced or cord-reinforced rubber, leather, or otherwise, at least two of the plies being adapted to define between them exteriorly isolated chambers or cells, adapted to sealedly contain a fluid, such as glycerine or other liquid, or a gas or gaseous mixture, such as air.

The chambers or cells are herein referred to as pneumatic or air chambers or cells because air is one of the recommended fluids, the word, air, when employed herein, referring to air, or alternatively to any other suitable fluid. Any one or some or all of said plies are not necessarily co-extensive with the entire structure, which is divided into a plural-chamber-constituting part and into a solid, generally attenuated, part. The term, solid, when employed herein, refers to the part of the support wherein no definite, deliberately designed air chamber or cell obtains and that consists of one or a plurality of mutually adjoining layers of suitable, preferably resilient, material. Such a structure would be conceivably a layer of sponge rubber sheathed on both sides with canvas-reinforced rubber or plain sheet rubber or leather or a combination of the foregoing and/or other materials.

An object and advantage of my invention consists in the provision of scientific correction for abnormal functioning of the human foot, whether acquired or congenital and whether it derives from muscle or ligament weakness or strain or the like, as well as in the provision of alleviation for non-correctible cases of the foregoing and of alleviation for not-yet-surgically corrected structural abnormalities, such as, for example, calcaneal spurs on the heel.

An important object and advantage consists in the provision of wide individual applicability, in a truly scientific clinical spirit, of every one of a number of basic invention-embodying supports to every kind of foot disorder for which the supports may be indicated, the number of different basic supports being determined solely by the necessary different lengths and widths in the various combinations, excepting for some supports provided with extensions of the basic structure

2

corresponding to air cells or chambers for the support of the first phalangeal-metatarsal joint.

Another object and advantage consists in the provision of structural economy without sacrifice in the consistent, durable performance of the support.

Additional objects and advantages manifest themselves thruout this specification, supplemented by the accompanying drawings, for which views of typical, but not of all possible, embodiments have been selected as suitable subjects, the views being schematic ones showing only the contours, in plan view, of the various air chambers and solid parts of the supports; the general art is so old and well established that, to persons skilled in it, a large number of different materials and assembling methods, all more or less satisfactory, are known, and any one of said materials and assembling methods are applicable to embodiments of the instant invention.

Figures 1, 2, 3, 4, 5 and 6 show said typical embodiments, which are respectively indicated by 16, 41, 42, 43, 44 and 15.

It is manifest that, in common to all embodiments, there are an inner or long longitudinal arch supporting chamber or cell 16 and two auxiliary air chambers or cells, although the invention can be embodied in supports having, in addition to the long longitudinal arch chamber, also referred to as the standard cell or chamber, a single or several auxiliary chambers, also referred to as complementary chambers or cells, from all of which, it is manifest, the standard chamber is in every instance isolated.

Referring to Figure 1, this support is provided with the half-elliptical, functionally complete heel-supporting heel chamber 17 and the anterior- or transverse-arch-supporting simple metatarsal chamber 18, both communicating with one another thru the there intervening medial exchange duct 19. Marginally, but not in area, chamber 17 is coextensive with the heel; the incompleteness is with respect to the indentation 28, constituting a recess to accommodate a calcaneal spur on the heel. The position of chamber 18 corresponds with the foot locus immediately behind the second, third and fourth metatarsal heads, also referred to as metatarsals, just as the position of the main or standard chamber 16 corresponds to the medial side of the inner or long longitudinal

arch. In both cases, the two chambers allow the respective muscles and ligaments to shorten and strengthen for eventual unaided support thereby of the respective bones. Standard chamber 16 is always isolated because the kind and degree of support for the long arch are substantially constant for all positions of the foot, whether when standing or in locomotion. When walking, the first impact is received on the heel, which impact is cushioned by the mass of air in chamber 17, this mass being immediately thereupon transferred under pressure therefrom thru the medial exchange duct 19 into the metatarsal cell 18, constituting it into a transitory cushion for receipt thereon of the next impact, whereupon the cycle begins to be repeated as long as the walking continues. In the case of communicating chambers, the total mass of air admitted to them is such as to inflate the anterior said chamber to a height of about three-eighths of an inch, with the posterior said chamber collapsed, to which rule of inflation there is an exception, to which reference will be had during the description of Figure 4. My experience teaches me that, in the majority of cases, the three-eighths of an inch for inflation height is the most comfortable and beneficial.

Referring to Figure 2, the simple metatarsal chamber 18 of Figure 1 has here been replaced by the modified metatarsal chamber 18A, designed to support the transverse or metatarsal arch behind the fifth as well as behind the second, third and fourth metatarsal heads, and also to support the short or outer longitudinal arch by the extension 18B of cell 18A, which extension extends to the inner incomplete heel chamber 20, with which chamber 18A therefore communicates. This extension, because of its relative attenuated form, functions somewhat similarly to the exchange duct 19 in Figure 1. This disposition of cells accords lateral balance to the foot and prevents inrolling or pronation.

Referring to Figure 3, the modified metatarsal chamber 18A communicates, thru the extension 18B, with the cuboid chamber 21, which adjoins and directly communicates with the outer incomplete heel chamber 22. Also present is an isolated scaphoid cell 23, supporting the scaphoid bone. Chamber 21 supports the cuboid bone. The function of cell 22 corresponds partly to the function of the complete heel cell in Figure 1.

Referring to Figure 4, the metatarsal cell 18 communicates, thru the medial exchange duct 19, with the enlarged inner incomplete heel chamber 24, functioning similarly to cell 20 in Figure 1, the indentation or recess for the calcaneal spur being indicated by 35. Additionally included are the anterior marginal cell 25, the outer incomplete heel chamber 26 and the there intervening outer exchange duct 27, the three sections being isolated from the other air sections but coacting with them in alleviation of or treatment of metatarsalgia or Morton's Toe, and cushioning the metatarsal heads. In order to assure that there is always at least a mass of air in cell 25 sufficient for the support of the metatarsal heads, I inflate sections 25, 26 and 27 with more air in proportion to their total volume than in the case of other combinations of communicating cells, referred to in the sixth paragraph of this specification. The anterior marginal cell 25 constitutes a pier for the metatarsal heads.

Referring to Figure 5, a composite metatarsal cell, consisting of the first metatarsal cell section 29, the metatarsal arch cell section 30 and the fifth metatarsal cell section 31, communicates, thru the exchange duct 32, with the combined cuboid and fifth metatarsal base cell 33, approximating a short or outer longitudinal arch cell, which in turn communicates, thru exchange duct 34, with modified heel cell 36, its calcaneal spur recess being indicated by 37.

Referring to Figure 6, a metatarsal cell 18 communicates, thru duct 19, with modified heel cell 17, whose calcaneal heel spur recess is indicated by 28. The numeral 38 indicates a first-phalangeal-metatarsal-joint cell correcting for hypermobility, shortness of the first metatarsal or looseness in said joint. Cell 38 is preferably mounted on a pier constituted from a relatively thick extension of the ply or plies constituting the solid part of the support. During the transfer of air from cell 18 to cell 17, a small amount thereof finds itself trapped in cell 39, which supports the anterior section of the outer longitudinal arch. Cell 39 cushions the digital nerves and supports the fifth metatarsal. During the transfer of air from cell 17 to cell 18, a small amount thereof finds itself trapped in cell 40, which cushions the cuboid bone.

No attempt has been made to describe all possible combinations of cells as it would needlessly burden this specification and the accompanying drawings. With the exception of the isolated standard cell supporting the inner longitudinal arch, every other cell may be made to communicate with or be isolated from every and any other cell, or cells, this relationship being determined by the particular abnormality for which treatment or alleviation is indicated.

I claim:

40 In a pneumatic foot support, the combination of a base member having an inflatable pneumatic cushion in a forward position to underlie the ball of the foot; a second inflatable pneumatic cushion in a rearward position adapted to underlie the heel of the foot, the member having a restricted passageway connecting said pneumatic cushions, a sufficient supply of pneumatic fluid in said connected cushions to completely inflate only one of said cushions so that shifting of the weight from the heel to the ball of the foot during walking causes flow of said pneumatic fluid from one to the other of the inflatable cushions through said passageway; and a third and fully inflated pneumatic chamber on the member in a central position to underlie the principal arch of the foot, said chamber being pneumatically isolated from the cushions and from said passageway.

60 WHITMAN W. DAVIS.
